[57] ABSTRACT

A camera shutter timing network includes a photoconductor connected in series with a plurality of diodes, the voltage across the diodes which is a logarithmic function of the photoconductor incident light is amplified by a variable gain amplifier to produce a first voltage. A second diode network combined with variable resistors and an amplifier produces a second voltage which is a logarithmic function of the camera diaphragm opening and film speed rating. A memory capacitor is charged to the difference of the two voltages and a timing capacitor is charged through a diode type logarithmic expansion network at a constant rate dependent on the memory capacitor voltage. An electromagnet energized through a Schmitt type switch releases the shutter to closing upon a predetermined voltage on the timing capacitor. A meter indicates the difference between the first and second voltages and hence the shutter speed.

AUTOMATIC TIMING NETWORK FOR CAMERA SHUTTERS

BACKGROUND OF THE INVENTION

The present invention relates generally to improvements in the automatic time control of camera shutters and it relates particularly to an improved network for the automatic closing of a single lens reflex camera in response to the incident light through the lens.

In conventional automatic exposure time control mechanisms for a single lens reflex camera, the exposure time control operation is performed in the following manner. During the preparatory operation for photographing such as viewing of the object or focusing, the object brightness is sensed by a photoconductor located in the path of the light from the object traversing the objective and entering the view finder. An electric charge of an amount corresponding to the sensed object brightness is temporarily memorized as a charge upon a capacitor. In synchronism with the shutter release operation the capacitor is inserted into another circuit, where the charged terminal voltage of said capacitor controls the exposure time.

In actual operation, in order to apply such operation factors as the diaphragm value, the sensitivity or speed value of the film used, etc. to the camera, a variable resistor for transforming such factor values to electric signals is coupled to the diaphragm setting ring and to the film sensitivity setting ring. After setting of the diaphragm value and the film sensitivity value through actuation of said setting rings, the power source switch of the network is closed, and the light measuring operation is performed during the photographing preparatory operation such as focusing. Upon depressing the shutter release button after completion of light measurement, a reflective mirror in the camera is swung up. Immediately before the mirror starts to move, the capacitor is inserted into another circuit. At this time, the light measurement value memorized as a charge upon the capacitor (including the conditions of the diaphragm value and film sensitivity value) controls the operation of another circuit. When the release is actuated and the shutter opening screen starts to run, a timing capacitor begins to be charged and time measurement based on the time constant value is started. When the time corresponding to the time measurement value has elapsed, the shutter closing screen is released by the operation of an electromagnet so that the shutter is closed. When the closing screen completes its movement, the mirror returns to its original position in the path of the light that has passed through the objective, and the mechanism returns to its initial state. Thus the photographing operation is completed. Upon advancing the film, the camera is prepared for the next photographing operation.

With such automatic exposure time control arrangement, the required exposure time control must be a time control inversely proportional to object brightness. Therefore with a photoconductor having a characteristic:

$Rc = KE^{-g}$, wherein Rc is the internal resistance value of the photoconductor element, E is the object brightness and K and g are constants characteristic of the element, it is required that $g = 1$. As is well known, however, it is hard to produce a photoconductor having a constant value of g within the variation range of 1:100,000, of the object brightness, and it is extremely difficult to obtain one with $g=1$. Further, it is very difficult to achieve uniform quality. Thus, among photoconductor elements factured under the quality control, there is variety of internal resistance Rc or g so that it is not easy to manufacture or select elements of the desired characteristic. In view of such circumstances, it is strongly desired that the above problem in light measurement be solved.

SUMMARY OF THE INVENTION

It is a principal object of the present invention to provide an improved automatic shutter control network for a camera.

Another object of the present invention is to provide an improved shutter timing network which is accurate over a wide brightness range with light sensitive elements of widely varying characteristics.

Still another object of the present invention is to provide an improved simple automatic shutter timing network having photoconductor g compensation and adjustments for such parameters as diaphragm value, film speed rating and the like.

A further object of the present invention is to provide in the arrangement of the above type a visual indication of the exposure time value determined by said proper automatic exposure time control operation with an evenly calibrated scale due to a linear voltage variation, prior to shutter release operation.

Still a further object of the present invention is to provide in the arrangement compensation for the influence of the ambient temperature upon its control operation so that proper exposure time control is always possible.

Another object of the present invention is to provide a network of the above characteristics which is readily built as a monolithic integrated circuit structure.

The above and other objects of the present invention will become apparent from a reading of the following description taken in conjunction with the accompanying drawings which illustrate preferred embodiments thereof.

In a sense the present invention contemplates the provision of a camera shutter timing network comprising a photoconductor having a resistance which is an exponential function of the light incident thereon, means coupled to said photoconductor for producing a control voltage which is a logarithmic function of the current in said photoconductor, and means responsive to the value of said control voltage for controlling the closing of said camera shutter. Advantageously the timing network comprises a photoconductor, a memory capacitor

first means for charging said memory capacitor to a voltage which is a function of said control voltage, a timing capacitor, second means for charging said timing capacitor at a constant current which is a function of the voltage across said memory capacitor, and third means responsive to the voltage across said timing capacitor for controlling the closing of said camera shutter.

In the preferred form, a photoconductor such as cadmium sulphide having an electric resistance characteristic of exponential variation in response to brightness variation is combined with logarithmic compression elements such as diodes so that the circuit will produce a voltage linearly varying in response to the exponential variation of brightness. This voltage is applied to a g compensation circuit to accomplish such

compensation that, while compensation is made of the non-uniformity of the photoconductor characteristic, in the operative circuit there is produced an appropriate electrical charge variation in a geometrical procession with a common ratio of 2 in response to factors applied from outside. As a result, the exposure setting condition such as the sensitivity value of the film used, the diaphragm value determined prior to photographing, the filter coefficient, etc. are transformed into a linear voltage variation which is then applied to the relevant apparatus. Then, computation is made by the circuit operation under said conditions and the resulting electrical variation amount is memorized as a charge on a capacitor. When the shutter is released, the voltage across said capacitor is transformed into a current corresponding to said electrical charge amount resulting from said computation through logarithmic expansion elements such as transistors. This current is utilized to constant-current charge a timing capacitor of constant capacitance so as to control the exposure time utilizing the time duration required by the voltage across the capacitor to rise up to a certain value.

BRIEF DESCRIPTION OF THE DRAWINGS

FIG. 1A is a block diagram of a network embodying the present invention employing an equilibrium type exposure factor control section;

FIG. 1B is a block diagram of a network embodying the present invention employing a non-equilibrium type exposure factor control section;

FIG. 2 is a circuit diagram of an example of an equilibrium type photographic measurement section according to the present invention;

FIG. 3 is a circuit diagram of an example of a non-equilibrium type photographic measurement section according to the present invention;

FIG. 4 is a circuit diagram of an example of memory retaining and logarithmic expansion circuits;

FIG. 5 is a circuit diagram of an example of a Schmitt circuit according to the present invention;

FIG. 6 is a circuit diagram of an example of stabilizing power source circuit in the system according to the present invention;

FIG. 7 is a circuit diagram of an example of the automatic shutter control system according to the present invention utilizing the equilibrium type photographic measurement section; and FIG. 8 is a circuit diagram of an example of the automatic shutter control system according to the present invention utilizing the non-equilibrium type photographic measurement section.

DESCRIPTION OF THE PREFERRED EMBODIMENTS

Referring now to the drawings, there are shown circuit networks, connected as illustrated and as hereinafter explained, including transistors T_n ($n = 1, 2, \dots, 37$), resistors r_n ($n = 1, 2, \dots, 19$), variable resistors $V_r n$ ($n = 1, 2, \dots, 10$), switches SW_B, SW_E, SW_F, SW_M and SW_T , a Zener diode ZD , an electromagnet Mg for releasably retaining the shutter closing screen in its cocked retracted position, a photoconductor CdS made of a material such as cadmium sulphide positioned in the path of light from the object which has passed through the objective lens and entered the viewfinder, a memorizing capacitor C_M , a timing capacitor C_T , an electric meter M for indicating the value to be set, and a power source battery E_B .

As shown in FIGS. 1A and 1B, the system according to the present invention is of two types differing in the manner of electric transformation of the diaphragm value and film sensitivity value in the photographic measurement section, namely the equilibrium type photographic measurement section and the non-equilibrium type photographic measurement section, respectively. First, the arrangement according to the present invention will be described with respect to the equilibrium type photographic measurement section, referring to one example thereof as shown in FIG. 2. The light from the object that has passed through the objective lens is transformed into photocurrent as controlled by the action of the photoconductor CdS . Then, owing to the diode action of the transistors T_1 and T_2 connected in series with the photoconductor CdS , a voltage $V_{D1,2}$ which is proportional to the logarithm of said photocurrent is developed at the junction of the photoconductor CdS and the transistor T_1 . In mathematical form:

$$R_{CdS} = k_1 I^a \quad (1)$$

wherein R_{CdS} is the internal resistance of the photoconductor CdS , I is the light input incident thereon, and k_1 and a are the characteristic constants of the particular photoconductor CdS .

Taking the logarithms of the both sides of the relation (1):

$$\log R_{CdS} = \log k_1 - g \log I \quad (2)$$

With respect to a logarithmic compression circuit due to the diode action of said transistor T_1 and T_2 , there exists the following relation:

$$\log R_{CdS} = \log k_2 - k_3 V_{D1,2} \quad (3)$$

wherein $V_{D1,2}$ is the voltage across the terminals of the transistors T_1 and T_2 , k_2 is a constant and k_3 is a compression constant. From the relations (2) and (3), the following relation results:

$$V_{D1,2} = (g/k_3) \log I + K_0 \quad (4)$$

wherein $K_0 = (1/k_3) \log (k_2/k_1) = \text{constant}$. Thus, through said circuit the light input I is transformed into a linearly varying voltage $V_{D1,2}$ wherein a logarithmic compression appears in the form of $(g/k_3) \log I$. The increment due to the light input in the relation (4) is:

$$V_{D1,2} = \frac{g}{k_3} \log I \quad (5)$$

Hereafter, signal input or output values provided with ' denotes the increment of the corresponding value.

In the g compensation circuit comprising the transistor T_3 , which the voltage $V_{D1,2}$ is its output signal, the resistor r_1 serially inserted in the collector circuit of the transistor T_3 and the circuit characteristic adjusting variable resistor V_{r1} serially inserted in the emitter circuit of the transistor T_3 , assuming the voltage gain thereof to be G_1 , the collector voltage V_{c3} is given as follows:

$$V_{c3} = -G_1 V_{D1,2} \quad (6)$$

Therefore, by adjusting said variable resistor V_{r1} , the circuit system of the present invention can be so compensated with respect to the g characteristic of the photoconductor CdS and the constants of circuit constituting elements that the circuit operates on the basis of the logarithmic expansion current which is proportionated to the light input signal.

The next stage emitter follower circuit comprising a transistor T_4 and a resistor r_2 serially connected in the emitter circuit thereof serves to perform an impedance transforming action for connection of the memorizing capacitor C_M . Assuming the voltage gain of this circuit to be G_2 , the signal voltage V_{e4} developed by the transistor T_4 at the emitter circuit thereof due to the light input signal is given as follows:

$$V_{e4} = G_2 (g/k_3) \log I \quad (7)$$

wherein $G_2 = -G_1 \times G_2$ ($G_2 \approx 1$). This signal voltage V_{e4} is the output of the light measuring block. This light measuring block serves to the timing section in cooperation with the diaphragm value and the film sensitivity value setting block to be hereinafter described.

A transformation which is similar to the transformation of light measuring block is also applied to the diaphragm and the film sensitivity value setting block comprising a variable resistor V_{r3} , which is coupled to the diaphragm value setting ring and to the film sensitivity setting ring in a manner well known in the art in the conventional camera of the subject type in order to be set in accordance with the diaphragm value and the film sensitivity value, a logarithmic compression circuit consisting of transistors T_9 and T_{10} serially connected to said variable resistor V_{r3} , a g compensation circuit consisting of a transistor T_8 , a resistor r_6 and a variable resistor V_{r2} , and an emitter follower circuit consisting of a transistor T_7 and a resistor r_5 .

When the resistance R_3 of the variable resistor V_{r3} is determined in response to the diaphragm value and the film sensitivity value, with respect to the logarithmic compression circuit due to the diode action of the transistor T_9 and T_{10} , the following relation is established;

$$R_3 = \log k_5 - k_6 V_{D9,10} \quad (8)$$

wherein $V_{D9,10}$ is the voltage across the terminals of the transistor T_9 and T_{10} , k_5 is a constant, and k_6 is a compression constant. The signal increment in the set value is:

$$V_{D9,10} = -\frac{1}{k_6} \log R_3 \quad (9)$$

Assuming the voltage gain of the g compensation circuit to be G_4 , the signal increment voltage V_{e8} in the collector voltage of the transistor T_8 is:

$$V_{e8} = -G_4 V_{D9,10} = \frac{G_4}{k_6} \log R_3 \quad (10)$$

The signal increment voltage V_{e7} appearing in the emitter voltage of the transistor T_7 due to the action of the emitter follower circuit is:

$$V_{e7} = G_5 V_{e8} \div V_{e8} \quad (11)$$

wherein G_5 is the voltage gain of the transistor T_7 ($G_5 \approx 1$).

Now, to the said memorizing capacitor C_M is applied a voltage of a value which is the difference between said voltage V_{e7} in response to the set value input signal and said voltage V_{e4} in response to the light input signal. The voltage gains of the circuits must be suitably adjusted so that the increment of V_{e4} corresponding to the one step of the light input varying in a geometrical procession with the common ratio 2 is equal to the increment of V_{e7} corresponding to the one step of the diaphragm value or the film sensitivity value varying in a similar manner.

An emitter follower circuit comprising a transistor T_5 , a resistor r_3 , a transistor T_6 and a resistor r_4 functions as a buffer for the output voltage V_{e4} due to said light input signal and the output voltage $V_{e4'}$ due to said set value input signal and serves as a driving circuit for the indication of exposure time with the electric meter M .

Referring now to FIG. 3 which illustrates the non-equilibrium photographic measurement section which is another example of the measurement section of the system according to the present invention, the light input signal voltage due to the action of the photoconductor CdS and other circuit elements is the same as described in connection with the network shown in FIG. 2. However, the arrangement for obtaining the signal of set values such as the diaphragm value and the film sensitivity value is different from that in the example as shown in FIG. 2. A constantcurrent circuit is established with transistors T_9 , T_{10} and T_{11} , a variable resistor V_{r2} , and resistors r_6 , r_7 and r_8 . In the collector circuit of the transistor T_9 there are serially connected a variable resistor V_{r3} for transforming of diaphragm value and a variable resistor V_{r4} for transforming of film sensitivity value and an adjusting variable resistor V_{r5} for adjusting DC operating point, the variable resistors V_{r3} and V_{r4} being independently coupled to the diaphragm value setting ring and the film sensitivity value setting ring respectively and being of such characteristic that the resistance varies linearly with the turning operation of the corresponding rings respectively.

Accordingly, assuming now the supply voltage to be V_{cc} , the emitter voltage V_{e11} of the silicon PNP transistor T_{11} is given as follows:

$$V_{e11} = \frac{r_8}{r_7 + r_8} \cdot V_{cc} + V_{BE11} \quad (12)$$

wherein V_{BE11} is the base-emitter voltage of the transistor T_{11} in operating, and r_7 and r_8 are the resistance of the resistor r_7 and r_8 respectively. Assuming that a current I_B flows through the variable resistor V_{r2} in the current adjustment,

$$I_B = \frac{V_{e11} - V_{BE10}}{V_{r2}} = \frac{(r_8/(r_7 + r_8)) V_{cc} + V_{BE11} - V_{BE10}}{V_{r2}} \quad (13)$$

wherein V_{BE10} is the base-emitter voltage of the transistor T_{10} in operating. If the temperature dependence of voltage V_{BE10} is equal to that of voltage V_{BE11} , then I_B is always constant irrespective of the ambient temperature variation. Therefore, if DC current amplification factor $h_{FE} \gg 1$ in the transistor T_9 and T_{10} ,

$$I_B \approx I_{c9} \quad (14)$$

wherein I_{c9} is the collector current of the transistor T_9 . Thus the collector current of the transistor T_9 turns out to be a constant current. In order to carry out the diaphragm value and the film sensitivity value transformation in this state through setting of the values of said variable resistors V_{r3} and V_{r4} , a circuit shall be established which satisfies the following condition: In the following relation (15) ΔR or I_{c9} is to be so selected that the emitter voltage increment $\Delta V_{e4'}$ of the transistor T_4 in response to one step change of the light input signal is equal to the emitter voltage increment $\Delta V_{e7'}$ of the transistor T_7 in response to one step change of the diaphragm value and the film sensitivity value:

$$\Delta V_{e4'} = \Delta V_{e7'} = \Delta R_{F, ASA} \times I_{c9} \times G_5 \quad (15)$$

wherein $\Delta R_{F, ASA}$ is the one step variation of the values of the variable resistors V_{r3} and V_{r4} in response to the diaphragm value and the film sensitivity value, and G_5 is the voltage gain of the Darlington connection circuit comprising the transistor T_7 and T_8 and the resistor r_5 ($G_5 \approx 1$).

The main function of the variable resistor V_{r3} is to compensate through adjustment of the resistance thereof the non-equilibrium of the D.C. operation level due to the non-equilibrium circuit system. Further function of the variable resistor V_{r4} is, however, to carry out compensation for the non-uniformity of the resistance of the photoconductor CdS so as to compensate the indication level of the exposure time on the electric meter M , in a very ready manner and independently of the diaphragm value transformation and the film sensitivity value transformation.

The Darlington connection circuit comprising the transistors T_7 and T_8 and the resistor r_5 serves as a buffer not to exert influence due to load upon the diaphragm value and the film sensitivity value setting section, and also serves to compensate the temperature dependence of the emitter voltage of the transistor T_4 on the light input signal side.

The operation of other arrangements, such as the electric meter M , of this non-equilibrium type photographic measurement section is the same as the case with the equilibrium type photographic measurement section as shown in FIG. 2.

In FIG. 4 there is shown the timing section of the system according to the present invention. In a three stage Darlington circuit comprising transistors T_{17} , T_{18} and T_{19} and a resistor r_9 and a logarithmic expansion circuit comprising transistors T_{20} and T_{21} , the base input signal voltage V_{in} of the transistor T_{17} is given as follows:

$$V_{in} = G_3 k_4 \log I_c = k_4^* \log I_c \quad (16)$$

wherein I_c is the collector current of the transistor T_{20} , k_4 is the expansion constant, G_3 is the voltage gain of the Darlington connection circuit comprising the transistors T_{17} , T_{18} and T_{19} and the resistor r_9 ($G_3 \approx 1$), and $k_4^* = G_3 k_4$.

For obtaining a current which is proportional to the light input in the system according to the present invention, from the relations (7) and (16) the following relation shall be established:

$$G_1^* (g/k_3) \log I = k_4^* \log I_c \text{, so that the following relation must result:}$$

$$G_1^* = (k_3 k_4^* / g) \quad (17)$$

When the resultant voltage gain G_1^* which consists of the voltage gain G_1 of the g compensation circuit of the light measuring block and the voltage gain G_2 of the emitter follower circuit comprised of the transistor T_4 , is so determined as to satisfy the relation (17), then the operation characteristics of this circuit system, including the g of the photoelectrical characteristics of the photoconductor CdS, is properly compensated so that a current which is proportional to the light input signal can be obtained as the collector current of the transistor T_{20} .

The retaining circuit and the logarithmic expansion circuit of the timing section is described below in conjunction with the network shown in FIG. 4. The structural coupling of the shutter timing network according to the present invention with camera mechanism is fundamentally the same as that of the conventional cameras of this type. In the system according to the present invention, however, the function of retaining the input signal voltage is performed by a high input impedance circuit comprising the memorizing capacitor C_M and the transistors T_{17} , T_{18} and T_{19} . The result of computation in the photographic measurement section is stored through the switch SW_M in the memorizing capacitor C_M . When a release button is depressed, the resulting release action causes the switch SW_M to be changed over from the photographic measurement section to the timing section just before the upswing of the mirror, and the photographic measurement section voltage V_{out} across the memorizing capacitor C_M is applied between the collector of the transistor T_{18} and the base of the transistor T_{17} as the timing section input voltage V_{in} . Since the retaining circuit comprising the transistors T_{17} , T_{18} and T_{19} and the resistor r_9 has a high input impedance characteristic due to

three stage Darlington network, the output voltage across the memorizing capacitor C_M of the result of the computation retains the time necessary for shutter action as the input voltage V_{in} of the timing section. In the logarithmic expansion and constant current charging circuit comprising a transistor T_{20} and T_{21} , the logarithmic expansion action is made through the diode characteristic between the base and the emitter of the transistor T_{20} and the diode action of the transistor T_{21} , and further, utilizing the collector characteristics of the transistor T_{20} , the timing capacitor C_T is charged by a constant-current.

In the embodiment illustrated by FIGS. 7 and 8 a memory switch SW_M of bipolar double throw type is used for storing the operational output from the photographic measurement section into a memorizing capacitor C_M . Such a memory switch SW_M , however, may be replaced by a bipolar single throw switch SW_M' having the equal efficiency.

With said bipolar single throw switch SW_M' , during the operation of measurement (SW_M' being ON), the base terminal of the transistor T_{17} is connected through the switch SW_M' to the emitter terminal of the transistor T_7 while the Darlington circuit of later stage comprising the transistors T_{17} , T_{18} and T_{19} , and the resistor r_9 is interrupted (i.e., inactive). The emitter terminal voltage of the transistor T_7 is, therefore, never influenced by connection of the base terminal of the transistor T_{17} with the emitter terminal of the transistor T_7 . On the other hand, the collector terminal of the transistor T_{13} is in connection through the high resistance R_M and the memory switch SW_M' with the emitter terminal of the transistor T_4 . An influence to which the emitter terminal voltage of the transistor T_4 might be subjected is negligible when the collector terminal of the transistor T_{13} is through the high resistance R_M to the emitter terminal of the transistor T_4 . Thus, the memory switch may be of bipolar single throw type having an arrangement as mentioned above.

There is hereinafter described the optimum operation point (bias point) in practical use of the retaining circuit and the logarithmic expansion circuit comprising the transistors T_{17} to T_{21} .

Assuming the base-emitter voltages of the operation points of the transistors T_{17} to T_{21} to be V_{BE17} to V_{BE21} respectively, the base potential V_{B17} of the transistor T_{17} is given as follows:

$$V_{B17} = V_{BE17} + V_{BE18} + V_{BE19} + V_{BE20} + V_{BE21} \quad (18)$$

This is the base potential of the transistor T_{17} in case of the collector current $I_c = 0$ (actually, there is a dark current) in the transistor T_{20} , and is the optimum operation point, that is, the bias point (voltage). As indicated by the relation (18), V_{B17} is composed only of base-emitter voltages V_{BE} 's which are of the greatest temperature dependence in silicon transistors, consideration must be made sufficiently of temperature compensation. Thus, with respect to the requirements on this bias point, that is, the bias voltage V_{BE17} given by the relation (18) and its temperature dependability, the optimum operation point indicated by the relation (18) is given by a bias circuit comprising the transistors T_{12} to T_{16} and the variable resistors V_{r6} and V_{r7} and further, there is performed a temperature compensation operation for compensating the increment of the expansion current (the collector current of the transistor T_{20}) due to temperature change in relation to the base-emitter voltages V_{BE17} to V_{BE21} . In this bias circuit, the variable resistor V_{r6} is provided mainly for regulating the circuit current of the transistors T_{12} to T_{16} and the variable resistor V_{r7} is provided mainly for regulating the collectors voltage V_{c13} of the transistor T_{13} . The variable resistors V_{r6} and V_{r7} may be so adjusted as to establish the following relation:

$$V_{c13} = V_{BE17} + V_{BE18} + V_{BE19} + V_{BE20} + V_{BE21} = V_{B17} \quad (19)$$

Also, since in this bias circuit the relation between the bias voltage and the temperature dependence can be regulated within a certain range, it is possible to select such operation point in the logarithmic expansion circuit that the widest logarithmic expansion characteristic range is obtained, and further, general regulations such as compensation of D.C. level in the photographic measurement section and regulation of exposure time are possible.

The result of the computation from the photographic measurement section is applied between the collector terminal of the transistor T_{13} and the base terminal of the transistor T_{17} as a timing section input voltage V_{in} . This timing section input voltage V_{in} is given as follows (cf. the relation (16)):

$$V_{in} \approx V_{out} \\ V_{in} = G_3 k_4 \log I_c \quad (20)$$

wherein G_3 is the voltage gain of the retaining circuit ($G_3 \approx 1$) and k_4 is the expansion constant.

When the switch SW_T is changed over from "on" to "off" in synchronism with the start of the camera shutter opening screen, the timing capacitor C_T starts to be charged by the charging current I_c due to the input voltage V_{in} . The voltage V_{CT} across the capacitor C_T is given as follows:

$$V_{CT} = \frac{1}{C_T} \int I_c \cdot dt$$

20

wherein C_T is the capacitance of the timing capacitor C_T . Since the charging current I_c is constant due to the collector characteristic of the transistor T_{20} ,

$$V_{CT} = (I_c t / C_T) \quad (21)$$

wherein t is the time. Accordingly, if the value V_{CT} is selected for the change-over level V_{SW} of the Schmitt circuit, the time T_d required by V_{CT} to rise from 0 up to V_{SW} is given as follows:

$$T_d = (C_T V_{SW} / I_c) \quad (22)$$

Therefore, the required delay time T_d is obtained by properly selecting the values of V_{SW} , C_T , and I_c , and thus the camera shutter closing screen can start its run after elapse of the time T_d after the start of run of the camera shutter opening screen, the required exposure time being automatically controlled in accordance with the photographing conditions.

The non-uniformity of the capacitance of the timing capacitor C_T can be compensated by adjusting the Schmitt change-over level V_{SW} or the charging current I_c in accordance with the relation (22). Adjustment of the Schmitt change-over level V_{SW} can be readily performed by adjusting the variable resistor V_{r8} of FIG. 5; and also adjustment of the charging current I_c can be readily performed by adjusting the variable resistor V_{r7} or V_{r8} of FIG. 4. This is very advantageous in the mass production of the network.

An explanation of the Schmitt circuit section is given below with reference to the example as shown in FIG. 5. In the high input impedance Schmitt circuit comprising transistors T_{22} to T_{28} and resistors r_{11} to r_{13} , when the switch SW_T is closed the transistors T_{22} to T_{24} are conducting the transistors T_{25} to T_{28} are non-conducting. Accordingly, through the buffer circuit comprising a transistor T_{29} and resistors r_{14} and r_{15} , a transistor T_{30} is conducting so that an electromagnet M_0 maintains its energized state. In the arrangement of this type, when the timing capacitor C_T is charged and the transistors T_{22} to T_{24} are conducting, the input impedance as seen from the base side of the transistor T_{22} is inserted in parallel with the constant-current charging circuit. Accordingly, the range of the charging current I_c is restricted so that it is necessary to introduce the three-stage Darlington connection high input impedance Schmitt circuit.

In the practical application of such circuit, however, the base-emitter voltage of each transistor causes the change-over level V_{SW} to be changed due to temperature change. Especially when the power source is of low voltage and the circuit comprises silicon transistors, such circuit system would not be very practical without any temperature compensation.

For this purpose, it is possible that, to the Schmitt circuit comprising the transistors T_{22} to T_{28} and the resistors r_{11} to r_{13} there is added the constant-voltage circuit for temperature compensation (three stage Darlington connection circuit) in series with the power source so as to compensate the temperature dependence of the change-over level V_{SW} of Schmitt circuit.

Assuming that the supply voltage to be V_{cc} , the change-over level V_{SW} of the Schmitt circuit is given as follows:

$V_{SW} =$

$$(V_{BE22} + V_{BE23} + V_{BE24}) - (V_{BE31} + V_{BE32} + V_{BE33}) \\ + \frac{r_{12}}{r_{11} + r_{12}} (V_{BE31} + V_{BE32} + V_{BE33} - V_{BE25} - V_{BE26} - V_{BE27} \\ V_{BE28}) + V_{ce} \left(\frac{r_{12}}{r_{11} + r_{12}} + \frac{R_9}{r_{17} + R_9} - \frac{r_{12}}{r_{11} + r_{12}} \frac{R_9}{r_{17} + R_9} \right) \quad (23)$$

wherein V_{BE22} to V_{BE33} are the base-emitter voltages of the transistors T_{22} to T_{33} respectively in operation, and r_{11} - r_{17} and R_9 are the values of resistors r_{11} to r_{17} and variable resistor V_{ce} respectively.

From the relation (23) it is known that the temperature dependence of V_{SW} is determined by the temperature dependence of the base-emitter voltage V_{BE} of each transistor. Accordingly, the overall temperature dependence of V_{SW} will be compensated to such an extent that it can be ignored if, in the relation (23), the temperature dependence of the parenthesized first and second terms cancel each other and in the parenthesized third term a value of the order of 1/10 is selected for the coefficient $r_{12}/(r_{11} + r_{12})$. Thus it is possible to obtain a high input impedance type Schmitt circuit having a very small temperature dependence of the change-over level.

As seen in the above example, the utilization of the same types of silicon transistors is particularly effective in case a monolithic IC structure is used.

By utilizing the fact that the change-over level can be shifted by varying the voltage of the temperature compensation constant-voltage circuit serially connected with said Schmitt circuit power supply by the adjustment of a variable resistor V_{ce} , it is possible to compensate the non-uniformity of the capacitance of the timing capacitor C_T or the non-uniformity of the exposure time due to that of delay time caused by non-uniformity of elements in circuit.

In cameras of such type, fluctuation of the supply voltage for operation exerts a direct influence upon the exposure time control operation so that it is necessary to stabilize this supply voltage. In the system according to the present invention, the stabilized power supply as shown in FIG. 6 is utilized so that the accurate exposure time control is always possible irrespectively of the fluctuation of the terminal voltage of battery. In the circuit of power supply there are provided an NPN type transistor T_{34} and a PNP type transistor T_{37} in a complementary connection so that an especially high stabilizing performance is assured at times when the terminal voltage of the battery is low and the stabilized output voltage is relatively high.

Two examples of the present invention utilizing the above described networks are shown in FIG. 7 (with the equilibrium type photographic measurement section) and in FIG. 8 (with the non-equilibrium type photographic measurement section).

Thus, the coupling action of the arrangement according to the present invention is almost the same as that of the conventional one of this type. In operation, first the light-input voltage transformation is carried out through the logarithmic compression of the light input by means of a combination of a photoconductor and logarithmic compression elements, then, through a g compensation circuit, said voltage is compensated to be of contemplated g characteristic irrespectively of the non-uniformity of the g characteristic of the photoconductor so as to obtain a linear voltage corresponding to the light input. On the other hand, the setting conditions such as the diaphragm value and the sensitivity of the film used are also electrically transformed into a linear voltage so as to apply these to the arrangement, and the result of the combination of these two linear voltages are utilized to charge the memorizing capacitor. Accordingly, an accurate exposure time control can be accomplished because the operation is not influenced by the photoconductor characteristic and regulation of the light input and the set value input signal is carried out in an accurate and simple manner. Further, in the arrangement according to the present invention, the light input signal and the set value input signal are both transformed into linear voltages

and these linear voltages are differentially combined and the result is indicated by an electric meter or other instrument. Therefore, the user can know the automatically controlled exposure time prior to the photographing operation. This is very advantageous in the practical operation because the set values can be reviewed and be reset in accordance with the particular photographing conditions.

With the non-equilibrium photographic measurement section, the diaphragm value, the film sensitivity value, etc., can be electrically transformed by means of independent transforming devices respectively so that the coupling between the arrangement and the camera can be advantageously simplified. In a constant-current circuit utilizing a transistor collector characteristic for the electrical transformation of

diaphragm value and film sensitivity value, to the bias circuit thereof there is added a diode connection circuit of transistors of the same type, and further, the bias circuit current is stabilized with respect to the ambient temperature by means of inverse-polarity transistors. Accordingly, with a constant-current characteristic, temperature compensation and stabilization of supply voltage fluctuation compensation can be carried out so that the arrangement can be operated always in a stabilized state and proper exposure time control can be performed.

Further, while the light input signal and set value input signal are separately compensated properly in the photographic measurement section, these signals can be also compensated properly in an overall manner in the timing section. Thus, two-stage compensation can be carried out so that the arrangement can be caused to operate properly.

While the arrangement according to the present invention can be constituted by conventional circuit elements. A monolithic integrated circuit can be very advantageously utilized in constituting it to obtain good results both in its manufacturing and in its operation too.

While there has been described and illustrated a preferred embodiment of the present invention it is apparent that numerous alterations, omissions and additions may be made without departing from the spirit thereof.

What is claimed is:

1. A camera shutter timing network comprising a photosensitive device having a first electrical parameter which is a function of the light incident thereon, a memory capacitor, means for charging said memory capacitor to a voltage which is responsive to a logarithmic function of said electrical parameter, a timing capacitor, means for charging said timing capacitor at a constant rate which is a function of the voltage on said memory capacitor, and switch means responsive to the voltage on said timing capacitor for controlling said camera shutter, said memory capacitor charging means including a logarithmic compression network coupled to said photosensitive device and an adjustable gain amplifier having an input connected to the output of said compression network.

5. The network of claim 1 wherein said compression network comprises at least one diode connected in series with said photoconductor.

3. The network of claim 1 including means for producing an adjustable second electrical parameter which is related to the camera diaphragm opening value and the speed value of the camera film, said memory capacitor voltage being responsive to the difference between the logarithms of said electrical parameters.

4. The network of claim 3 including means for providing a visual indication of said parameter difference.

5. The network of claim 1 wherein said charging rate is a function of the antilog of said memory capacitor voltage.

6. The network of claim 5 including means for producing an adjustable second electrical parameter which is related to the camera diaphragm opening and the speed value of the camera film, said memory capacitor voltage being responsive to a function of the logarithms of said parameters.

7. A camera provided with an automatic exposure time control shutter system and a system measuring light through the photographic taking lens, characterized by a light measuring

block comprising a photosensitive element, means including a logarithmic compression network and an amplifier for providing a first output which is logarithmic function of the light incident on said photosensitive element, a diaphragm value and film sensitivity value setting block including a variable resistor for providing a second output which is a logarithmic function of said values, a memory capacitor, means for charging said memory capacitor to a voltage which is an arithmetic function of said first and second outputs, a timing capacitor, and means including a logarithmic expansion circuit and a constant-current charging network for charging said timing capacitor at a constant rate which is an antilog function of said voltage whereby said timing capacitor is constant-current charged with a current which is proportional to the incident light amount in synchronism with the start of the camera shutter opening and means including a switching circuit responsive to the charge on said timing capacitor for controlling said shutter whereby there is produced a delay time between the run start of the shutter opening and that of the shutter closing and control is so made that after elapse of such delay time the closing is initiated.

8. A camera according to claim 7 comprising an indicating device responsive to the charge on said memory capacitor so that the automatically set exposure time is indicated prior to shutter release action.

9. A camera shutter timing network comprising

- a. a photosensitive element;
- b. first means including a logarithmic compression network coupled to said photosensitive element for providing a first signal responsive to a logarithmic function of the light incident on said photosensitive element;
- c. second means including a variable resistor for providing a second signal which is a logarithmic function of at least one non-light photographic parameter;

- d. a memory capacitor;
- e. means for charging said memory capacitor to a voltage which is an arithmetic function of said first and second signals;
- f. a timing capacitor;
- g. second means for charging said timing capacitor at a rate which is an antilog function of said memory capacitor voltage; and
- h. means responsive to the charge on said timing capacitor for controlling said camera shutter timing.

10. The network of claim 9 wherein said memory capacitor charging means charges said memory capacitor to a voltage which is a function of the arithmetic difference between said first and second signals.

- 11. A camera shutter timing network comprising:
  - a. A photosensitive element;
  - b. first means including a network coupled to said photosensitive element for providing a first signal responsive to a logarithmic function of the light incident on said photosensitive element;
  - c. second means including a variable resistor for providing a second signal which is a logarithmic function of at least one non-light photographic parameter;
  - d. a memory capacitor;
  - e. means for charging said memory capacitor to a voltage which is an arithmetic function of said first and second signals;
  - f. a timing capacitor;
  - g. second means including a logarithmic expansion circuit for charging said timing capacitor at a rate which is an antilog function of said memory capacitor voltage; and
  - h. means responsive to the charge on said timing capacitor for controlling said camera shutter timing.
